FORNIA.

DRY-CHEMICAL FIRE-EXTINGUISHER.

1,354,093.

Specification of Letters Patent. Patented Sept. 28, 1920.

Application filed July 2, 1919. Serial No. 308,216.

To all whom it may concern:

Be it known that I, CHARLES S. DAVIDSON, a citizen of the United States, residing at Los Angeles, in the county of Los Angeles 5 and State of California, have invented a new and useful Dry-Chemical Fire-Extinguisher, of which the following is a specification.

This invention relates to fire extinguishers 10 and especially to that type constructed and adapted to spray a dry chemical mixture of powders upon the flames to extinguish them.

An object of the invention in general is to 15 make provision for extinguishing flames with a combination or mixture of chemicals in powder form.

Another object of the invention is to produce an apparatus of this character of comparatively simple construction and one that 20 is reliable in operation.

Another object is to construct an apparatus of this character which can be conveniently carried on the back of the operator, or otherwise as desired.

5 The accompanying drawings illustrate the invention:

Figure 1 is a vertical mid section of a fire extinguisher built in accordance with the provisions of this invention, a mixture of 10 powdered chemicals being shown in the container.

Fig. 2 is a plan section on line indicated by x^2-x^2 , Fig. 1.

There is provided a container or reservoir 15 of suitable shape and of substantially air tight construction. The ends 2, 2' of the container are provided with bearings 3 to journal a shaft 4 which is provided with stirring blades 5, there being any required number of said stirring blades. The bottom end 2' of the container is provided with a stuffing box 6 to minimize leakage around the shaft 4. The shaft 4 is provided with a crank 7 whereby the shaft may be turned to rotate the blades 5 so as to stir and mix the powdered chemicals placed in the lower portion of the container 1, said chemicals being indicated by the character 8.

The upper end 2 of the container is provided with an opening 9 into which is screw-threaded the nipple 10 of a pressure gage 11. The pressure gage 11 may be removed when it is desired to charge the container with the chemicals. The upper end 2 of the

container is provided with a valved hose 55 coupling 12 adapted to be connected by a hose, not shown, to a supply of compressed air.

Near the bottom 2' of the container 1 the peripheral wall of said container is provided with a port 13 into which is screw-threaded a valve 14 that connects with a tube 15 fastened by clips 16 to the outer face of the container 1, said tube 15 extending longitudinally of the container and terminating adjacent the upper end 2 of said container. Connected to the tube 15 by a coupling 17 is a hose 18 provided with a nozzle 19.

In practice, to put the apparatus in condition for use, the pressure gage 11 will be removed and the lower portion of the container will be charged through the opening 9 with dry chemicals in powdered form and of such character that they are capable of 75 extinguishing flames. Such dry chemicals are well known in the art pertaining to chemical fire extinguishers and therefore a detailed description herein of the chemicals is unnecessary. After the chemicals have 80 been introduced to the container, the hose coupling 12 will be connected with a suitable source of compressed air supply and the upper portion of the container or space above the chemical charge will be charged 85 with compressed air. The air pressure employed may be forty pounds per square inch more or less.

After, or before, the container has been charged with the chemicals and compressed 90 air, the chemicals will be thoroughly mixed by turning the crank 7. The apparatus is now ready for use and to extinguish a fire the operator will open the valve 14, whereupon the chemical mixture will be forced by 95 the compressed air through the tube 15 and hose 18 and the chemical mixture will issue from the nozzle 19 in the form of a dry spray. The operator will direct the dry chemical spray upon the fire until it is extinguished. For convenience in using, the operator may strap the container onto his back. It is understood that the container 1 will be maintained in more or less upright position so that the chemical mixture will be 100 in the lower portion of the container adjacent the port 13, in order that the air pressure will be available behind the chemicals.

for forcing said chemicals out of the container through the port 13.

I am aware that liquid chemicals have heretofore been employed in fire extinguishing apparatus and that the chemicals are of such nature that when they are brought together by inverting of the container the chemicals produce a gas which acts to discharge the liquid upon the flames, but an advantage of employing dry chemicals and compressed air in combination to effect spraying of the powdered chemicals is that the fire can be extinguished much quicker than by the use of liquid chemicals. Another advantage of using the dry chemicals and compressed air lies in the ease with which the apparatus may be prepared for use and maintained at maximum efficiency.

The dry chemicals in the container 1 will not deteriorate and they may be thoroughly mixed at suitable intervals and prevented from caking or cakes already formed may be broken up by a few turns of the crank 7. The pressure gage 11 constantly indicates the amount of air pressure and if said air pressure is reduced below a certain value by reason of any slight leakage of air from the container or by reason of using the apparatus, the hose coupling 12 will be connected with the compressed air supply and

the pressure will be brought up to a desirable maximum.

It is understood that the invention is not limited to the exact details of construction shown in the drawings and described above, 35 but that the invention also includes such changes and modifications as lie within the spirit and scope of the appended claim.

I claim:

In a dry chemical fire extinguisher, a container in the form of a cylinder having a port adjacent its lower end, a valve for said port, a tube connected with the valve and extending to the upper end of the container, a hose fastened to the upper end of the tube, 45 bearings in the opposite ends of the container, a shaft extending from end to end of the container and journaled in said bearings and having one end projecting outside of the container, a crank on the projecting 50 end of the shaft, and stirring blades on the shaft extending at right angles thereto inside of the container.

Signed at Los Angeles, California, this 25th day of June 1919.

CHARLES S. DAVIDSON.
